(57) **CLAIM**

The ornamental design for a display screen with graphical user interface, as shown and described.

DESCRIPTION

The FIGURE is a front view of a display screen with graphical user interface, according to the present invention. The dash-dot-dash broken lines in the FIGURE showing the display screen illustrate environmental subject matter that forms no part of the claimed design.

The dash-dash broken lines in the FIGURE illustrate portions of the graphical user interface that form no part of the claimed design.
